DESIGN FOR A SHOE ORNAMENT

Pearl F. Ashton, Providence, R. I., assignor to Ernest E. Weller, Providence, R. I.

Application April 27, 1940, Serial No. 92,000

Term of patent 3½ years

To all whom it may concern:

Be it known that I, Pearl F. Ashton, a citizen of the United States, residing at Providence, in the county of Providence and State of Rhode Island, have invented a new, original, and ornamental Design for a Shoe Ornament, of which the following is a specification, reference being had to the accompanying drawing, forming a part thereof.

Fig. 1 is a top plan view of a shoe ornament showing my new design;

Fig. 2 is a side elevation; and

Fig. 3 is an end elevation thereof.

I claim:

The ornamental design for a shoe ornament, substantially as shown.

PEARL F. ASHTON.
